UNITED STATES PATENT OFFICE.

LORENZ FLICK, OF SAYLESVILLE, RHODE ISLAND, ASSIGNOR TO SAYLES FINISHING PLANTS INC., OF SAYLESVILLE, RHODE ISLAND, A CORPORATION OF RHODE ISLAND.

ORNAMENTED FABRIC AND METHOD OF ORNAMENTING IT.

Application filed April 14, 1925. Serial No. 23,121.

To all whom it may concern:

Be it known that I, LORENZ FLICK, a citizen of the United States, residing at Saylesville, in the county of Providence and State 5 of Rhode Island, have invented an Improvement in Ornamented Fabrics and Methods of Ornamenting Them, of which the following description, in connection with the accompanying drawings, is a specification, like 10 characters on the drawings representing like parts.

This invention relates to ornamented fabric and to a method of producing the ornamentations.

15 In the Lorenz Flick Patent No. 1,521,363, granted December 30, 1924, is described and claimed a fabric that is ornamented by contrasting designs formed of flock, and the contrasting effect is obtained by forming 20 some designs of heavy thick deposits of flock while other designs are formed of thin narrow deposits of flock.

The present invention relates to a further development of the invention of said patent, 25 and in the present case a more pronounced contrast in the fabric ornamentation is produced by printing a colored substance on portions of the fabric and by forming deposits of flock upon other portions of the 30 fabric.

The ornamental effect of the present invention is particularly pleasing when portions of the same design are formed of the colored substance while other portions are 35 formed of the flock; for example, if the design represents a flower the effect is very pleasing if part of the flower is formed by the colored substance and the rest by the flock deposits.

40 In producing the contrasting ornamentations upon the fabric it is desirable that both ornamentations be placed upon the fabric while it passes thru a single machine, so that the ornamentations will be accurately 45 positioned in relation to each other. In carrying out the invention it is not practical to apply the flock deposits first and then the colored adhesive, since the pressure of the color applying roll upon the fabric might 50 crush the flock deposits. It is therefore necessary to apply the colored adhesive first, but this leads to difficulties, because the colored adhesive printed upon the fabric must

be dried before it reaches the flock applying means to prevent the flock from sticking to the colored adhesive. 55

Heretofore, in printing designs upon fabric, it has been customary to use a colored adhesive that required to be steamed to set the same, but this type of adhesive could 60 not be used satisfactorily in carrying out the present invention because of the difficulty of drying the steamed fabric before it reached the flock applying portion of the machine. 65

To overcome this difficulty a quick-drying, color-carrying adhesive is used, and in carrying out the method of the present invention, the quick-drying adhesive is printed upon the fabric where the colored 70 design is desired; the printed fabric is then heated to dry the color adhesive, and flock securing adhesive is then printed upon the fabric in a wet condition where the flock deposits are desired; the flock is then applied to the fabric so that it will become embedded in the wet adhesive, after which this adhesive is dried and the excess flock not held by the adhesive is removed. As a result 75 an ornamented fabric is produced in which 80 part of each design may be produced by the colored substance and the rest of the design by the raised flock deposits.

The ornamented fabric of the present invention and method of producing the same 85 will be best understood from the following description when read in connection with the accompanying drawings:

In the drawings:

Fig. 1 is a plan view of a piece of fabric 90 having the color adhesive applied to form part of the different designs.

Fig. 2 is a plan view of the same piece of fabric having the flock deposits applied to complete the ornamentation of the fabric. 95

Fig. 3 is a diagrammatic view of one form of machine for carrying out the method of the present invention.

Fig. 4 on an enlarged scale is a vertical sectional view thru a portion of the ornamented fabric of Fig. 2, the section being taken on line 4-4. 100

In carrying out the present invention the ornamentations may be applied to a fabric 10 having any preferred color, and, while 105 the texture and weave of the fabric may

vary extensively, the structure of the fabric preferably is such that the adhesive applied to the fabric will penetrate thru the same.

The colored adhesive is printed upon the fabric as indicated by 11 in Fig. 1, to form a predetermined portion of each design, and the flock deposits 12 are then formed upon the fabric to complete the designs as shown in Fig. 2. The configuration and general 10 appearance of the designs may be varied as desired, and in Fig. 2 the left-hand design represents a group or reef of flowers having the contrasting color effect, while the right-hand design of Fig. 2 is given the form of 15 a geometrical figure having the contrasting color effect.

Since the colored adhesive and flock deposits are preferably applied to the fabric in rapid succession, the colored adhesive 20 should have the property of drying quickly and of becoming set without being steamed. It should also be nonsoluble in water so that the ornamented fabric may be laundered, and it is found that an adhesive 25 formed of a cellulose solution meets these requirements satisfactorily. The desired color may be imparted to the adhesive by pigments, by powdered metallic particles, or by other substances that will produce a pleasing 30 design upon the fabric. The width and thickness of the flock deposits may be varied as desired, but particularly pleasing effects are obtained by applying the contrasting 35 ornamentations to a relatively thin colored fabric having the design portions 11 produced in a color different from that of the fabric, while the remaining portions of the designs are formed by thick heavy deposits 12 of white or colored flock. As a result the flock 40 deposits are non-transparent and stand out boldly, as shown in Fig. 4, in marked contrast to the colored portions 11 of the designs and the different color of the fabric.

In practicing the method of the present 45 invention to produce the new ornamented fabric, the colored adhesive 11 is printed upon the fabric as shown in Fig. 1, and then the flock deposits 12 are applied in a definite relation to the colored portions 11, as 50 shown in Fig. 2.

One good form of machine for carrying 55 out the present method is shown diagrammatically in Fig. 3, wherein the fabric 10 to be ornamented is drawn from the supply roll 13 to the color printing roll 14, where it passes between the roll and a backing roll 15 about which passes the back grey 16 such as is commonly employed. The quick-drying colored adhesive may be supplied to the 60 printing roll 14 by a roll 17 that dips into the adhesive supplying trough 18, and it will be understood that the back grey passes downwardly from a supply roll not shown about the backing roll 15 and then upwardly to a take-up roll not shown. It

is assumed that the fabric 10 being ornamented is relatively thin so that the colored adhesive will penetrate thru the fabric and produce the colored design on each face thereof.

As stated, the colored adhesive employed is a quick drying adhesive which can be dried upon the fabric by the time it reaches the flock applying position, and in order to dry the adhesive quickly the fabric 10 upon 75 leaving the printing roll 14 passes thru a heating chamber which may have the heating pipes 19.

The fabric 10, upon leaving the heating chamber, passes between an adhesive applying roll 20 and a backing roll 21 and the backing roll 21 is provided with a back grey 22 similar to the back grey 16. The adhesive applying roll 20 may be a perforated or 80 stenciled roll having means 23 within the roll for supplying the adhesive.

After the wet adhesive has been printed on the fabric by the roll 20 the flock is applied to the fabric, and in the construction shown this is accomplished by causing the fabric to pass beneath a rotating perforated cylinder 24 which is filled with flock and throws the flock outwardly as it rotates. A hood 25 supported over the cylinder serves to direct the flock downwardly upon the fabric. The flock preferably is applied to the fabric in a relatively thick layer over the face of the fabric so that it will cover and stick to the wet adhesive deposits.

The fabric 10 with the layer of flock thereupon passes from the flock applying means to the feed rolls 26 within a drying chamber 27. From these rolls it passes upwardly about a feed roll 28 and is then looped over bars 29 that are passed lengthwise of the upper portion of the drying chamber 27 by spaced endless chains 30 supported at the opposite sides of the drying chamber. The chamber 27 may be heated by pipes 31, and by the time the loops of fabric reach the delivery end of the drying chamber the flock securing adhesive will be thoroughly dried, whereupon the excess flock may be brushed off of the fabric without injuring the raised flock deposits 12 that remain where the flock securing adhesive was applied and are firmly secured to the fabric by the dry adhesive.

This completes the ornamentation of the fabric in accordance with the present invention, and the designs formed in part 120 by the colored adhesive and in part by the flock deposits will stand out in marked contrast and produce a pleasing effect.

What is claimed is:—

1. The process described for ornamenting 125 fabric with designs having contrasting portions, which consists in printing a colored quick-drying adhesive upon the fabric to form part of the complete designs, drying the colored adhesive, printing a flock secur- 130

- ing adhesive upon the fabric where the remaining portion of each design is to appear, then depositing loose flock upon the wet adhesive, drying the flock securing adhesive with the flock embedded therein, and removing the excess flock not secured to the fabric by the adhesive to complete the designs. 5 of each design being formed of a colored substance printed upon the fabric, and the remaining portion of each design being formed of flock deposits adhesively secured to portions of the fabric other than that to which the colored adhesive is secured. 35
2. The process described for ornamenting woven fabric with contrasting colors, which 10 consists in printing a colored quick-drying adhesive upon the fabric to form part of the ornamentation, drying the colored adhesive, printing a flock securing adhesive upon the fabric where a different ornamentation is desired, then depositing the loose flock upon the wet adhesive, drying the flock securing adhesive with the flock embedded therein, and removing the excess flock not retained by the adhesive. 15 5. As a new article of manufacture, a woven fabric ornamented by designs having contrasting portions, one portion of each design being formed of a colored substance printed upon the fabric, and the remaining portion of each design being formed of flock deposits adhesively secured to the fabric and having a sufficient thickness to stand out 45 from the surface of the fabric to a pronounced degree, and the flock and colored substance being applied to different portions of the fabric in spaced relation to each other. 50
3. As a new article of manufacture, a woven fabric ornamented by designs having contrasting portions, one portion of each design being formed of a water-insoluble colored-adhesive printed upon the fabric, and the remaining portion of each design being formed of flock deposits adhesively secured to portions of the fabric other than that to which the colored adhesive is secured. 45 5. As a new article of manufacture, a woven fabric ornamented by contrasting colors produced by a colored substance printed upon portions of its surface and by flock deposits adhesively secured to other portions 55 of its surface so that the flock deposits are placed upon different portions of the fabric from that upon which the colored substance is applied. 6. As a new article of manufacture, a fabric ornamented by designs portions of which are formed in contrasting colors, one portion
4. As a new article of manufacture, a fabric ornamented by designs portions of which are formed in contrasting colors, one portion
- In testimony whereof, I have signed my 60 name to this specification.

LORENZ FLICK.
